UNITED STATES PATENT OFFICE.

FIN SPARRE, OF WILMINGTON, DELAWARE, ASSIGNOR TO THE E. I. DU PONT DE NEMOURS POWDER COMPANY, OF WILMINGTON, DELAWARE, A CORPORATION OF NEW JERSEY.

EXPLOSIVE AND PROCESS OF MAKING SAME.

No. 850,326.

Specification of Letters Patent.

Patented April 16, 1907.

Application filed January 25, 1907. Serial No. 353,965.

To all whom it may concern:

Be it known that I, FIN SPARRE, a subject of the King of Norway, residing at Wilmington, county of Newcastle, and State of Delaware, have invented a new and useful Improvement in Explosives and Processes of Making Same, of which the following is a full, clear, and exact description.

In a patent issued to me February 20, 1906, No. 812,958, I have described an ammonium-nitrate metallic explosive containing ungelatinized nitrocellulose which is safe, non-freezing, and capable of being compressed without loss of detonating force. In an application filed by me October 24, 1905, Serial No. 284,152, I have described a composition for making such safety explosive waterproof and the process of making such composition. In an application filed by me May 31, 1906, Serial No. 319,491, I have described such a waterproof safety explosive and the process of making same. In an application filed by me November 28, 1905, Serial No. 289,422, I have described an improved process of incorporating the ingredients of such waterproof safety explosive.

The present invention relates to an improved composition embodying the inventions of said patents and the process of making said composition.

The following is an example of my improved composition and process: Ammonium nitrate, fifty parts, is mixed at an elevated temperature—say 90° centigrade—35 with a previously-melted mixture consisting of dinitrobenzin, eight parts, and mono-nitrobenzin, two parts. After a half hour's intimate mixing, preferably in a rolling-mill in a steam-jacketed pan, the mass is allowed 40 to cool. This mass may be called "mixture No. 1." Potassium nitrate, twenty parts; ferrosilicon, ten parts, and nitrocellulose, ten parts, are incorporated without artificial heat for one hour, preferably in an ordinary rolling-mill or pulverizing-barrel. This mass 45 may be called "mixture No. 2." Mixtures Nos. 1 and 2 are finally incorporated together without artificial heat for another hour, preferably in an ordinary mill or pul-50 verizing-barrel.

In place of dinitrobenzin any other solid nitro compound of a hydrocarbon will be found more or less efficient. In place of

mononitrobenzin any other liquid nitro compound of a hydrocarbon will be found more or less efficient. In place of potassium nitrate any other non-hygroscopic nitrate, such as nitrate of barium, may be employed. In place of ferrosilicon may be employed a metal such as aluminum or any metallic alloy or any sulfid, carbid, or silicid of a metal that will physically and chemically act as a metal to raise the temperature of combustion, and thus act as quickening agents to increase the force and velocity of the explosion. In place of nitrocellulose may be employed nitrostarch, nitromannite, or other solid organic nitrates performing sensitizing functions. The resultant composition forms an excellent explosive for general blasting purposes. It is waterproof, almost non-hygroscopic, non-freezing, absolutely safe, and possesses great strength.

While ammonium nitrate is hygroscopic, it is in this explosive coated with a non-crystallized waterproof mixture which tends to repel moisture and water. The explosive really consists of two physically-mixed or independent parts, one part comprising the coated and protected ammonium nitrate and the other part comprising the sensitizing agent, the metallic ingredient, and the non-hygroscopic oxygen-carrier. By the force of the detonating charge of fulminate the second part of the powder is caused to detonate, which in turn detonates the first or remaining part of the powder.

The essential part of the invention consists in employing as the base of the powder ammonium nitrate having a waterproof coating incorporated with the mixture of a sensitizing agent, a metallic ingredient, (or ingredient acting as a metal,) and a non-hygroscopic oxygen-carrier that is not coated. If a quick and powerful explosive is desired, the metallic ingredient should be intimately incorporated with the non-hygroscopic oxygen-carrier, with which mixture the sensitizing agent should be intimately incorporated. The ingredients will not, however, if the proportion of the sensitizing agent is within proper limits (twenty-five per cent. as a maximum) for a safe and economical explosive, form a detonating explosive without ammonium nitrate.

The use of my improved composition is not

necessarily restricted to blasting, but may be employed, for example, as a shell-bursting charge. As an example of a composition suitable for a shell-bursting charge the following may be mentioned: Ammonium nitrate, forty-five parts, is incorporated for one hour at an elevated temperature with a melted mixture of mononitrotoluol, two parts, and dinitrotoluol, eight parts, forming mixture No. 1. Nitrocellulose, eighteen parts; ferrosilicon, twelve parts, and potassium nitrate, fifteen parts, are incorporated cold for two hours, forming mixture No. 2. The two mixtures are then incorporated cold for one hour.

Having now fully described my invention, what I claim, and desire to protect by Letters Patent, is—

1. An explosive comprising a mixture of ammonium nitrate and a waterproof coating therefor, incorporated with a mixture of a solid, uncoated, non-hygroscopic inorganic oxidizing agent, ferrosilicon, and a nitrated organic sensitizing agent, substantially as described.

2. An explosive comprising a mixture of ammonium nitrate and a waterproof coating therefor containing a nitro compound of a hydrocarbon, incorporated with a mixture of a solid, uncoated non-hygroscopic inorganic oxidizing agent, ferrosilicon, and a nitrated organic sensitizing agent, substantially as described.

3. An explosive comprising a mixture of ammonium nitrate and a waterproof coating therefor containing a solid nitro compound of a hydrocarbon and a liquid nitro compound of a hydrocarbon, incorporated with a mixture of a solid, uncoated, non-hygroscopic inorganic oxygen carrier, ferrosilicon, and a nitrated organic sensitizing agent, substantially as described.

4. An explosive comprising a mixture of ammonium nitrate and a waterproof coating therefor containing a solid nitro compound of a hydrocarbon and a liquid nitro compound of a hydrocarbon, incorporated with a mixture of ungelatinized nitrocellulose, ferrosilicon and uncoated potassium nitrate, substantially as described.

5. An explosive comprising a waterproof coating mixture containing a liquid nitro compound of a hydrocarbon less than five per cent. and a solid nitro compound of a hydrocarbon five to fifteen per cent., ammonium nitrate less than sixty-five per cent. incorporated therewith, and a mixture containing a nitrated organic sensitizing agent five to twenty-five per cent., ferrosilicon five to twenty per cent. and uncoated potassium nitrate ten to forty per cent., substantially as described.

6. An explosive comprising a mixture of ammonium nitrate less than sixty-five per cent., a waterproof coating therefor six to

twenty per cent., incorporated with a mixture of a solid, uncoated, non-hygroscopic, inorganic oxidizing agent ten to forty per cent., ferrosilicon five to twenty per cent. and a nitrated organic sensitizing agent five to twenty-five per cent., substantially as described.

7. An explosive comprising a mixture of ammonium nitrate less than sixty-five per cent., a waterproof coating therefor six to twenty per cent. containing a nitro compound of a hydrocarbon, incorporated with a mixture of a solid, uncoated, non-hygroscopic inorganic oxidizing agent ten to forty per cent., ferrosilicon five to twenty percent. and a nitrated organic sensitizing agent five to twenty-five per cent., substantially as described.

8. An explosive comprising a waterproof coating mixture containing a liquid nitro compound of a hydrocarbon less than five per cent. and a solid nitro compound of a hydrocarbon five to fifteen per cent., ammonium nitrate less than sixty-five per cent. incorporated therewith, and a mixture containing a nitrated organic sensitizing agent five to twenty-five per cent., ferrosilicon five to twenty per cent. and a solid, uncoated, non-hygroscopic, inorganic oxidizing agent ten to forty per cent., substantially as described.

9. The process of making an ammonium-nitrate metallic explosive containing a nitrated organic sensitizing agent which consists in incorporating ammonium nitrate with a waterproof coating ingredient, separately incorporating ferrosilicon and the sensitizing agent with a solid, uncoated, non-hygroscopic, inorganic oxidizing agent, and then incorporating the two mixtures, substantially as described.

10. The process of making an ammonium-nitrate metallic explosive containing a nitrated organic sensitizing agent which consists in incorporating ammonium nitrate with a waterproof coating ingredient containing a nitro compound of a hydrocarbon, separately incorporating ferrosilicon and the sensitizing agent with a solid, uncoated, non-hygroscopic, inorganic oxidizing agent, and then incorporating the two mixtures, substantially as described.

11. The process of making an ammonium-nitrate metallic explosive containing a nitrated organic sensitizing agent which consists in incorporating ammonium nitrate with a liquid nitro compound of a hydrocarbon and a solid nitro compound of a hydrocarbon, separately incorporating ferrosilicon and the sensitizing agent with a solid, uncoated non-hygroscopic, inorganic oxidizing agent, and then incorporating the two mixtures, substantially as described.

12. The process of making an ammonium-nitrate metallic explosive containing ungel-

atinized nitrocellulose which consists in incorporating ammonium nitrate with a waterproof coating ingredient, separately incorporating the nitrocellulose, ferrosilicon and potassium nitrate, and then incorporating the two mixtures, substantially as described.

In testimony of which invention I have

hereunto set my hand, at Philadelphia, on this 24th day of January, 1907.

FIN SPARRE.
